UNITED STATES PATENT OFFICE.

WILLIAM WHARTON, JR., AND EDWARD SAMUEL, OF PHILADELPHIA,
PENNSYLVANIA, ASSIGNEES TO WILLIAM WHARTON, JR., & CO.,
(LIMITED,) OF SAME PLACE.

SWITCH FOR CABLE OR OTHER CONDUIT RAILWAYS.

SPECIFICATION forming part of Letters Patent No. 339,955, dated April 13, 1886.

Application filed November 23, 1885. Serial No. 183,708. (No model.)

To all whom it may concern:

Be it known that we, WILLIAM WHARTON, Jr., and EDWARD SAMUEL, both citizens of the United States, and residents of Philadelphia, Pennsylvania, have invented certain Improvements in Switches for Cable or other Conduit Railways, of which the following is a specification.

The object of our invention is to combine with a cable railway, where underground conduits are used, a switch which is operated by the weight of the draft-animals attached to the street-cars which run on the same tracks as the cable-cars, while the cars drawn by the cable pass over the switch upon their proper route entirely free from the control of the movable tongue.

In the accompanying drawings, Figure 1 is a plan view of part of a track and cable-conduit, showing our improved switch mechanism; Fig. 2, a section on the line 1 2, Fig. 1, part of this figure being on the line 3 4, Fig. 1. Fig. 3 is a perspective view of one of the switch-castings. Fig. 4 is a sectional diagram on the line 5 6, Fig. 1, illustrating the passage of double-tread wheels over the switch; and Fig. 5 is a sectional diagram on the line 5 6, illustrating the passage of single-tread wheels over the switch.

30 A A' are the switch-castings connecting the main and side tracks, the casting A being provided with a pivoted movable tongue, a, as shown in Figs. 1 and 3.

B is a box, preferably made of cast-iron, to 35 contain the operative parts of the switch. This box is below the level of the road bed, and is cut out for the reception of the switch-castings.

Suspended on suitable pivot-blocks, b b, 40 formed on the sides of the box, is a rocking frame, D, having its opposite ends under two platforms, E E', which are flush with the road-bed when the rocking frame is in a horizontal position. The frame D is provided with projections d, on which the platforms E E' rest. Two fixed plates, F F', are placed over the 45 remaining portion of the box; but they are sufficiently far apart to leave a slot, n, to per-

mit the passage of the grip-bar of a cable-car, as described hereinafter. One end of the 50 rocking frame D is connected through the medium of a lug, d', to one arm of a bell-crank lever, G, pivoted to the box B at g, the other arm being connected to the movable tongue a of the switch A by a rod, h, as shown in Fig. 55 2. The box B has an opening, M, in each end, to correspond with the conduit and to allow the passage of the cable and the grip of a cable-car, the position of the cable being indicated in the present instance at x. 60

N N, Fig. 1, are the cable-conduits proper, which are secured to the box B, in the present instance, by rivets or bolts passing through a flange formed on the end of the conduit and through the end of the box. We depress the 65 arms of one side of the rocking frame D to form a yoke of sufficient size to allow a clear passage for the cable and the grip-bar mechanism, the plates F F' being, as above stated, fixed sufficiently far apart to form a continuation of the grip-slot n of the cable-conduit. 70

It should be understood that we do not limit ourselves to the precise form of mechanism shown for operating the switch, as different forms will readily suggest themselves. 75

Referring to Figs. 3, 4, and 5, and especially to Fig. 3, it will be noticed that the guard-rail s of the switch-casting A has inclined ends and is higher than the top of the switch-tongue a, so that the double-tread wheels of a cable-car when passing over the switch-casting A travel on this raised guard-rail s. 80

Referring to Fig. 4, W W' are the wheels of a cable-car, and are what are termed "double-tread" wheels—that is, they are provided with an extra tread, w, on the inside of the flange. 85

The wheels V V', illustrated in Fig. 5, are the wheels of a street-car drawn by draft-animals, and are the usual or single-tread 90 wheels.

It will be noticed on referring to Fig. 4 that the inside tread, w, of the wheel W' travels on the face of the raised guard-rail s, and that the wheel W' is thereby raised above 95 and is free from the control of the switch-

tongue a , the guard-rail s' on the rail A' at the same time preventing any accidental lateral movement of the cable-car in the direction of the arrow, Fig. 4. The rise or incline 5 of the guard-rail s begins at the points yy , at or near each end of the casting A , Fig. 3, and gradually reaches its full height at the two points zz . Thus it will be seen before the tread of the wheel W' can again rest on the 10 rail proper it has cleared the tongue a , and that any accident which might occur to a cable-car by reason of the switch-tongue being set for the side track is thus avoided, but when a car having the ordinary single-tread 15 wheels passes the switch it is directed either onto the main track or onto the side track, according to the way the switch-tongue is set. If, for instance, the plate E is depressed by a draft-animal of an advancing car with single- 20 tread wheels stepping upon it under the guidance of the driver, the frame D will be rocked to the position shown in Fig. 2, which will, through the medium of the bell-crank lever G and rod h , move the tongue a to the position 25 indicated in the drawings, and the car will be directed onto the side track; but if the draft-animal should tread on the plate E' the frame D will be rocked in the other direction and will be moved to a position opposite to 30 that shown, so that the car will be directed onto the main track.

Although we have shown in the drawings the route of the cable-cars to be the straight track, it is evident that the shape of the switch 35 can, if desired, be so modified or its position so changed that the cable-cars will be directed onto the side track without in the least departing from the features of our invention. In such case the regular route of the cable- 40 cars having double-tread wheels would be upon the side track, and they could never go upon the straight track; but the cars having single-tread wheels could, as before, be directed onto either the straight track or the 45 side track, as might be desired.

We wish it understood that we do not confine or limit ourselves to the application of our invention to cable railways alone, for while we have described the cars with double- 50 tread wheels as being drawn by a cable, it is evident that our invention can be used in connection with cars propelled by electricity or any other power where the conductor or other motive appliance is contained in an under- 55 ground conduit, and it is necessary to have a slot opening through the switch to allow the passage of a bar or other connection between the car and the conductor or other underground motive appliance.

60 The frame D can be so counterweighted as to balance the extra metal required on one

side of the center to form the yoke-shaped extension of the arms.

We prefer to have the rocking frame D with the depressed yoke-shaped arms on one 65 side constructed as shown in Fig. 2, so as to have the center of suspension, b , near the top of the box B , and yet to allow the free passage of the cable and the cable-grip bar at all times without interfering with the independent movement of the rocking frame; but it is evident that the center of oscillation and suspension of the rocking frame D can be so lowered that, without depressing any of its parts from a general plane, there will be room 70 above the rocking frame for the passage of the cable and the grip-bar.

We claim as our invention—

1. A switch-box, B , having a slot, n , for the passage of a cable-grip bar or a contact-bar.

2. A switch-box, B , having end openings, M , for the passage of a cable and a cable-grip bar or a contact-bar.

3. A switch-box, B , having a slot, n , for the passage of a cable-grip, and end openings, M , for the passage of a cable and a cable-grip bar.

4. A rocking frame, D , having its arms on one side depressed and continued around under and outside of the cable, substantially as set forth.

5. The combination of a railway-track, conduit for cable or other driving mechanism, movable platform, movable switch-point, and connecting mechanism for operating said switch-point from said movable platform passing beneath the driving mechanism in the conduit, all substantially as and for the purpose set forth.

6. The combination of switch-castings A and A' with a box having end openings, M and M' , and a slot, n , for the passage of the cable and of the grip-bar of a cable-car, all substantially as described.

7. The movable tongue of a switch and movable operating-platform connected to the said tongue, in combination with a box, B , having end openings, M and M' , and a slot, n , all substantially as described.

8. The raised inclined rail s , when combined with a movable tongue, a , and with movable operating-platforms connected to the said tongue.

In testimony whereof we have signed our names to this specification in the presence of two subscribing witnesses.

WILLIAM WHARTON, JR.
EDWARD SAMUEL.
